PENCIL HOLDER

Lazar Margulies, New York, N. Y.

Application May 18, 1945, Serial No. 594,575

4 Claims. (Cl. 120—103)

1

This invention relates to new and useful improvements in pencil holders, and has more particular reference to a gynecological tracer.

More particularly, the invention proposes a new and improved pencil holder which will serve to trace drawings of gynecological findings with the thumb of the examining hand while the patient is being examined so as to synchronize the drawings with the findings.

It is proposed to characterize the new and improved gynecological tracer by the fact that it includes a splint-like double shell adapted to engage upon the thumb and having shell sections hingedly connected at their front ends. Means is provided for locking the shell sections together for holding the interphalangeal joint of the thumb stiff. A pencil clamp is mounted on the top one of said shell sections. It is proposed that the material used for constructing the pencil holder be light, and easy to sterilize. For example it may be of aluminum, steel, brass, or even plastic, if the latter does not change its form during boiling.

Still further the invention contemplates numerous forms and designs of the new pencil holder. One modified form is shown in which the pencil clamp is adjustably mounted to assume various adjusted positions angular to the double shell.

Another object of the invention is the construction of a device as mentioned which is simple and durable and which may be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is an illustration of a pencil holder constructed in accordance with this invention and mounted on the thumb.

Fig. 2 is a side elevational view of the pencil holder.

Fig. 3 is a rear view of Fig. 2.

Fig. 4 is a front view of Fig. 2.

Fig. 5 is a top plan view of Fig. 2.

Fig. 6 is a bottom plan view of Fig. 2.

Fig. 7 is a plan view similar to Fig. 5 but illustrating a pencil holder constructed in accordance with a modification of this invention.

Fig. 8 is a fragmentary enlarged transverse ver-

2

tical sectional view taken on the line 8—8 of Fig. 7.

Fig. 9 is a fragmentary enlarged longitudinal vertical sectional view taken on the line 9—9 of Fig. 8.

The pencil holder, in accordance with this invention, includes a splint-like double shell consisting of a pair of shell sections 10 and 10' adapted to engage on the thumb. These shell sections 10 and 10' are hingedly connected by a hinge construction 11 at their front ends. A spring 12 is mounted upon the hinge 11 and acts to normally urge the shell sections 10 and 10' apart. Means is provided for locking the shell sections 10 and 10' together for holding the shell upon the thumb in a manner so as to hold the interphalangeal joint of the thumb stiff, as exact drawings are only possible with a stiffened interphalangeal joint of the thumb, and swaying of the pencil will thus be avoided.

This locking means includes a rack-like bolt 14 pivotally mounted by a pintle pin 15 upon one of the bottom shell section 10 and passing through an opening in a lug 16 formed on the top shell section 10'. A small spring 17 urges the rack-like bolt 14 against the edge of the opening in the lug 16 for locking the shell sections together.

A pencil clamp 20 is mounted on the top of the shell section 10'. This pencil clamp has a shank portion 21 by which it is engaged on the top shell section 10'. It also is provided with a cylinder-like clamp portion 22 which engages about the sides of a pencil for holding the pencil.

In Figs. 7-9 a modified form of the invention has been disclosed which is very similar to the prior form, distinguishing merely in the fact that the pencil clamp 20 is adjustably supported upon the top shell section 10'' so as to be capable of being moved to various adjusted positions. More particularly, the pencil clamp 20 is provided with a support shank 25 and which engages into a transverse groove 26 formed laterally across the top face of the shell section 10''.

A leaf spring 27 is mounted within the groove 26 and urges the shank 25 in one direction against one side of the groove 26. This latter side is formed with a tapered portion or wall 28 having serrations 28'. The adjacent face of the shank 25 is provided with complementary serrations 28''. The pencil clamp 20 may be manually forced in one direction so as to bow the spring 27 to disengage the serrations 28' of the shank 25 from the serrations and then the pencil clamp may be moved laterally in one direction or the other, as

desired. The shank may be located to hold the pencil at a most convenient position for an exact drawing to be made during the examination.

The pencil holder is used as follows: The gynecological examination is performed in the usual way and if the examiner finds aberrations from normal worth recording he will engage the pencil holder on the thumb of the inner examining hand, by forcing the shell sections against the sides of the thumb so that the ratchet-like bolt 14 will hold the shell sections in clamped positions. Thus, the shell sections hold the interphalangeal joint of the thumb stiff. Now the thumb may be used to trace a drawing of the gynecological findings simultaneously with the examination.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In a pencil holder having a pair of opposed semi-circular shell sections for engagement on opposite sides of a finger, a hinge pivotally connecting the shell sections together at their front ends, an arcuate rack bar pivotally mounted on one of the shell sections and formed along one edge with ratchet teeth, a lug extending from the side of the other shell section and formed with an opening through which said rack bar extends, and a spring mounted on the shell section which pivotally supports said rack bar and engaging and urging said rack bar into a position in which said ratchet teeth engage the material of said lug at one side of said opening, said ratchet teeth being directed to idle past said lug when the shell sections are moved together and to restrain movement of the shell sections when moved apart.

2. In a pencil holder having a pair of opposed semi-circular shell sections and a pencil clamp, means adjustably mounting the pencil clamp on one of the shell sections to be adjustable laterally relative thereto, comprising a support shank extending from the pencil clamp, a transverse groove formed in the face of the said one shell section, said groove being of a width greater than the thickness of said support shank and said support shank having its free end extended into said groove, means within said groove urging said support shank into facial contact with one side wall of said groove, serrations formed on the said one side wall of said groove, serrations formed on the face of said support shank adjacent the said one side wall and engaging said first-mentioned serrations to retain the support shank and the pencil clamp carried thereby against lateral movement relative to the shell section, whereby said support shank may be moved against the action of said means in a direction to separate said serrations to free said support shank and the pencil holder carried thereby to be moved laterally of the shell sections within said transverse groove.

3. In a pencil holder having a pair of opposed semi-circular shell sections and a pencil clamp, means adjustably mounting the pencil clamp on one of the shell sections to be adjustable laterally

relative thereto, comprising a support shank extending from the pencil clamp, a transverse groove formed in the face of the said one shell section, said groove being of a width greater than the thickness of said support shank and said support shank having its free end extended into said groove, means within said groove urging said support shank into facial contact with one side wall of said groove, serrations formed on the said one side wall of said groove, serrations formed on the face of said support shank adjacent the said one side wall and engaging said first-mentioned serrations to retain the support shank and the pencil clamp carried thereby against lateral movement relative to the shell section, whereby said support shank may be moved against the action of said means in a direction to separate said serrations to free said support shank and the pencil holder carried thereby to be moved laterally of the shell sections within said transverse groove, said means comprises a leaf spring mounted within said groove and bearing against the face of said support shank opposed to the face formed with said second-mentioned serrations.

4. In a pencil holder having a pair of opposed semi-circular shell sections and a pencil clamp, means adjustably mounting the pencil clamp on one of the shell sections to be adjustable laterally relative thereto, comprising a support shank extending from the pencil clamp, a transverse groove formed in the face of the said one shell section, said groove being of a width greater than the thickness of said support shank and said support shank having its free end extended into said groove, means within said groove urging said support shank into facial contact with one side wall of said groove, serrations formed on the said one side wall of said groove, serrations formed on the face of said support shank adjacent the said one side wall and engaging said first-mentioned serrations to retain the support shank and the pencil clamp carried thereby against lateral movement relative to the shell section, whereby said support shank may be moved against the action of said means in a direction to separate said serrations to free said support shank and the pencil holder carried thereby to be moved laterally of the shell sections within said transverse groove, said one side wall of said groove and said serrated face of said support shank being inclined toward said support shank to prevent disengagement of said support shank from said groove in the interengaged position of said serrations.
